UNITED STATES PATENT OFFICE.

JOHN C. RICHLBERG AND DAN BROBSTON, OF CHICAGO, ILLINOIS.

FIRE-ESCAPE.

SPECIFICATION forming part of Letters Patent No. 292,855, dated February 5, 1884.

Application filed March 26, 1883. (No model.)

To all whom it may concern:

Be it known that we, JOHN C. RICHLBERG and DAN BROBSTON, citizens of the United States, residing at Chicago, in the county of 5 Cook and State of Illinois, have jointly invented a new and useful Improvement in Fire-Escapes, of which the following is a specification.

Our invention relates to improvements in 10 a folding escape-ladder.

In reference to the accompanying drawings, Figure 1 represents in perspective view the front and rear part of the folding escape-ladder, the part between where broken away indicating its full length, and similar in construction as the remaining ones. Fig. 2 is a front view of the same, and Fig. 3 shows a part of the apparatus in side elevation.

The several matters of improvements will be 20 specified in the claim, and may be briefly stated, and consist in the construction of the subject.

A is a wire of selected quality and its strength satisfactorily tested to warrant perfect safety for the purpose, and cut in pieces of sufficient 25 length, intended to construct frames or sections in shape of squares of any desired size, but uniform each to the other. The wire is bent in right angles, four in number, around to accomplish the object, and, beginning at one 30 side, is formed first an upward-turning loop, *a*, at one end of the wire, the other end terminating into a similar loop, *b*, passed through the first one, and bent downward. Both looped and connected ends represent a knuckle-joint, 35 *C*, as this kind is most preferable for its self-tightening tendency and durable binding.

B is a piece of an iron pipe, in length corresponding with the sides of the square wire frame, and of satisfactory strength in regard 40 to material. The diameter of the pipe used is calculated to embrace two thicknesses of wire, as a pair of frames are intended to be inclosed together, and it is of great importance to the object in view to furnish room for free, radiant, 45 and undisturbed motion of the connected sections of wire frames. The ends of pipes are inside carefully rimmed out, as shown in the sectional view in Fig. 2 of the drawings, for the purpose of preventing possible cutting or 50 grinding the wire at that place.

F is simply a small frame, turning on the

top end of the upper frame, and made of the same size of wire as the frame itself, and is provided with a hook, *c*, to lift the folded ladder out of its resting-place, and to fasten a 55 valise or trunk with contents to it when lowered down to the ground for safety.

I is a grasp-handle attached on a rung at the window-sill, to enable a person in descending to catch hold when turning outside and 60 clinging to the escape-ladder, and is also made of strong wire *D D*, embracing and tightly fastened around the rung or pipe *B*, which latter turns freely on the wire frames, which it connects and folds and unfolds with the apparatus. The same attachment can be placed at 65 suitable distances and distributed along the entire length of the folding ladder, as a guard to prevent too close a contact with the side of a wall, and provides a space for foothold and 70 grasping.

Starting from the looped end *a* of the wire, the remaining part is bent at a desired distance, entering and passing there in a right-angular direction through the pipe *B*, appearing at the other end, where it is closely bent down to enter another piece of pipe equal in size and length and running in the same direction beyond as the former one, and when appearing again at the end of the second 80 pipe is finally bent to meet the starting-point of the looped piece of wire, and is united there to the same by passing the other end through the loop *a*, forming a similar loop, *b*, riding in the former one, and effecting a substantial joint, *C*, known as "knuckle-joint," 85 by twisting the joined pieces each around and against the other in a manner which allows them to get tightened more at the united part in proportion to the increased weight, load, or 90 strain, producing an immense power of resistance and strength, so necessary for a safe escape apparatus. The bent pieces of wire, in connection with the pipes, as described, represent a square frame or section, with looped 95 joint on one side. The following frames are made in the same way of manipulating the material, only the looped joint occurs at the opposite side of the frame or section, purposely so arranged on account of counterbalancing 100 the changing position and weight of a person in descending the apparatus, and causing tight-

ening, if any, equal on both sides. The frames or sections are united together by running the wire of the following frame parallel to the foregoing one through one of the pipes of the former frame, producing in sufficient additional extent a flexible ladder with crosswise-mounted pipes, serving as footholds and offering grasping parts in secured position.

The apparatus is kept in a folded condition 10 inside a room or any designated place in front of a window or exit, the frame or section nearest the floor securely fastened to the base-board or floor by use of strong eyebolts or hooks, and its use and location plainly shown by a 15 conspicuous printed card or label in the room and at the apparatus. In regard to using it,

it is operated by simply taking hold of the uppermost frame at the projecting hook *c*, and, after putting same outside of the window or exit, let go, when it unfolds itself quickly to 20 the ground.

We claim—

In a metallic flexible ladder, the combination, with the rungs thereof, of the handles consisting of the horizontal portion *I* and the 25 portion *D*, embracing the said rungs, substantially as set forth.

JOHN C. RICHBERG.
DAN BROBSTON.
